tion of America, a corporation of Delaware

Application June 14, 1947, Serial No. 754,758

14 Claims. (Cl. 179—171.5)

1

This application discloses a new and improved method of and means for modulating the amplitude of wave energy of carrier wave frequency in accordance with control potentials which may represent signals. It also discloses improved means for linearly demodulating frequency modulated energy and for converting frequency modulated energy to frequency and amplitude modulated energy.

In known forms of amplitude modulators such as those making use of multi-grid tubes, the percentage of linear modulation is limited to approximately 35%. A primary purpose of our invention is to provide modulation means which operates linearly for a larger percentage modulation. In our modulator, we produce well over 90% linear modulation.

To attain this purpose, we use a trigger or locking circuit having one position of stability, a differentiating circuit for supplying pulse energy of carrier wave frequency to the trigger circuit to flip the same from its stable position at the carrier rate. A condenser is charged by a constant current source which is varied by the modulation and this condenser is discharged by the trigger circuit when it is tripped out of its stable position. The charging current is a linear function of the modulation so that charging of the condenser is linear with respect to the modulation. The tripping rate and rate at which discharge of the condenser takes place are constant so that the charge in the condenser varies with the modulation. The voltage across the condenser, taken as output, is a carrier almost fully modulated in amplitude by the control potential or signal. In the embodiment described, the constant current is supplied by a pentode to the condenser wherein it is integrated. By the term "constant current" here, applicant means that the current is constant for each finite grid potential irrespective of changes in anode potential of the pentode.

The principle involved is with modification applicable to demodulation of frequency modulated energy and to conversion of such modulated energy to correspondingly amplitude and frequency modulated energy. Then the current integrated in the condenser fed by the pentode is not modulated but on the contrary is held constant and low enough not to trip the trigger circuit. The energy which is frequency modulated, is differentiated by a network including R and C and then applied as pulses to the trigger circuit to fire the same at a variable rate depending on the repetition rate of the frequency modulated energy. When the firing is at a high rate, the condenser will have a smaller charge because the charging intervals are short being measured by intervals between firing. When the firing rate is low, the condenser has more

charge. The output taken from the condenser will then be of varying amplitude as well as varying frequency. If this output is passed through a low pass filter whose cut-off is just above the highest modulation frequency, then the original modulation may be recovered at the filter output. Where frequency modulated energy is to be converted to correspondingly amplitude and frequency modulated energy, the output of the condenser is passed through a band pass filter which passes all components including the FM deviation band and its side bands.

It is believed that our invention as described above, will be understood by those versed in the art but details of various embodiments will now be described and in this description, reference will be made to the attached drawings. In the drawings,

Fig. 1 illustrates the essential elements of a trigger circuit, means for applying carrier energy thereto to trip the same to discharge a condenser and means for modulating the charge in said condenser all in accordance with our invention,

Fig. 2 illustrates a modification of the embodiment of Fig. 1,

Fig. 3 shows by curves the forms of the voltage waves appearing at different points in the circuits of Figs. 1 and 2,

Fig. 4 is a further modification of the arrangement of Fig. 1. Fig. 4 illustrates an embodiment of our improved demodulator or remodulator using the principles illustrated in Figs. 1 to 3 inclusive, and

Fig. 5 illustrates by curves the form of the waves appearing at different points in the embodiment of Fig. 4.

In Fig. 1, V1 is the modulator tube, V5 and V6 are the tubes of the locking or triggering circuit. The anode 6 of tube V5 is connected by resistor R5 to the positive terminal of a direct current source of potential B1, the negative terminal of which is grounded being thereby connected to the cathode of tube V5 through the one-way valve in the form of a diode tube V4, and/or a similar tube V3 and resistor R4 in parallel with tube V3. The anode 8 of tube V6 is connected through resistor R8 shunted by condenser C4 to the grid 10 of tube V5. This anode direct current circuit then runs from the negative terminal of source —B2 through the tube V6 resistor R8, resistor R6 in the grid circuit of tube V5 and back to ground and +B2. Tube V6 has a grid resistor R7 and the control grids 10 and 12 of tubes V5 and V6 are cross coupled there being a condenser C3 in the coupling between the anode 6 of tube V5 and the control grid 12 of tube V6. This is the triggering circuit having one condition of stability and at this condition of stability, tube V5 is cut-off while tube V6 draws heavy current to produce in

resistor R6 a large potential drop applying the necessary high negative bias to the control grid 10 of tube V5 to cut this tube off.

The carrier wave is applied at terminals 20 and impressed by differentiating condenser C1 and resistor R3 on the cathode of a one-wave valve in the form of a diode tube V2 having its anode connected to the cathode of tube V5. The modulator tube V1 has its anode 22 connected to the point P2 at the upper end of condenser C2 which is the integrating condenser for the modulation current. The tube V1 is a pentode and has its control grid variably coupled by resistor R1 to a modulating signal source at terminals 30. Its cathode is connected by resistor R2 to the negative terminal of the source B2, the positive terminal of which is grounded. The screen grid is connected to a point on a potential divider including resistors R12 and R13. The tube V1, therefore, has no anode direct current circuit except such as is provided from -B2 through resistor R2 through the impedance of tube V1 to point P2.

The tube V1 being a pentode has current flow which is constant with respect to grid bias irrespective of anode potential variation. This point is of importance to the understanding of my invention since the potential at point P2 and on the anode of V1 varies in accordance with the charge on condenser C2 which is linearly related to the potential on the grid of tube V1 and also varies to some extent in accordance with the differentiated carrier potential variations although these variations are slight due to the isolating effect of resistor R4.

The tubes V5 and V6 constitute a trigger circuit operating in a well known manner. As arranged, tube V5 is cut off by the negative potential on its grid 10 due to heavy current flowing in R6, through tube V6 which is fully conductive. This state of conductivity stands until an applied bias trips the locking circuit. Such a potential might be negative and applied to point P1 so that the potential on the cathode of tube V5 now approaches the potential on the grid 10 of tube V5 and heavy current flows through tube V5 to cut off tube V6 by applying a more negative pulse to its grid 12 through condenser C3. Tube V6 then remains cut-off for a time measured by the values of capacitor C3 and resistor R7. That is, during the time it takes the negative charge on C3 to leak off through resistor R7. The tube V6 then begins to draw current to apply a more negative potential to the control grid of tube V5 and the action is accumulative as is well known to trip the triggering circuit back to its one stable condition whereat tube V5 is fully cut off and tube V6 is fully conductive. The arrangement here is such that the bias at point P1, in the absence of carrier energy applied at C1, causes the triggering circuit to return to this one condition of stability in the event it is tripped therefrom.

Tube V1 has modulation applied to its grid and capacitor C2 is charged by current flow from ground and the negative terminal of source B2 to the positive terminal of source B2 through resistor R2, tube V1 and into condenser C2 to place a negative potential at the point P2 and on that side of condenser C2. This negative potential, however, is never sufficient to act, through one-way tube V3, on the cathode of tube V5 at point P1 to trip the trigger circuit out of its one condition of stability.

The carrier consists of square waves which are

differentiated by the capacitor and resistor C1, R3 to form pulses as shown in line A of Fig. 3. Diode tube V2 is poled and arranged so that only the negative pulses are passed on to point P1 and to the cathode of tube V5. Every negative pulse passed on to the cathode of tube V5 will reduce the positive potential on the cathode with respect to the grid 10 potential an amount sufficient to fire the trigger circuit and cause tube V5 to conduct and tube V6 to become non-conducting; that is, the trigger circuit is tripped out of its one stable condition.

When the tube V5 conducts, it discharges condenser C2; that is, the integrating condenser for the current, the magnitude of which is controlled by the modulation. This discharge path for condenser C2 is from ground and the negative terminal of source B4, condenser C2, tube V3 (and a slight amount through resistor R4), tube V5, resistor R5 to +B1 and back to ground and -B1. The tube V5 conducts for at least as long as the time required to discharge capacitor C2. The active time of the trigger circuit, which, as shown above, is determined primarily by a time constant (capacitor C3 and resistor R7) is slightly greater than the time required to discharge capacitor C2 and after condenser C2 is fully discharged, the one-way valve diode V4 supplies the additional current in the direct current output path of tube V5 to keep the tube V5 conducting. The resistor R4 is an isolating resistor between the cathode of tube V5 and capacitor C2 which prevents the pulses at P1 from affecting unduly the triangular waves at P2. The tube V3 supplies a low impedance path for the electrons from capacitor C2 and tube V4 to reach the output impedance of tube V5.

A summary of the operation will now be given even though it is thought the same will be clear from the foregoing description.

Constant current from tube V1 is integrated on condenser C2 causing the voltage across C2 to vary in proportion to the magnitude of the current and the time that it flows. C2 is of such value that the current flow from tube V1 never causes the voltage across C2 to be large enough to fire the trigger circuit. The firing is always done by the carrier pulses from tube V2 and recurs at a constant rate. The modulating signal applied to the grid of tube V1 will cause the current through tube V1 to vary. The current flow from tube V1 to condenser C2 is constant for any one value of grid signal voltage on tube V1, despite the variations in plate voltage of tube V1, i. e., tube V1 supplies a constant current to condenser C2. Any linear increase or decrease in signal voltage results in a linear increase or decrease in current flow into condenser C2. Since the trigger is fired at regular intervals, (C2 is discharged at regular intervals) the amplitude of the voltage across condenser C2 is a direct function of the magnitude of the current flow from tube V1, which is a direct function of the signal voltage on the grid of tube V1. The wave appearing at point P1 and on the cathode of tube V5 which fires the trigger circuit and results from a combination of the negative pulses at carrier frequency illustrated in line A of Fig. 3, formed by the differentiating network capacitor C1, resistor R3 and the one-way valve V2, and the linear charge across C2 is represented in line C of Fig. 3. Note that this voltage represents the linear charge across condenser C2 as well as the carrier pulse. The modulating potential applied to the grid of tube V1 is represented in line B of Fig. 3. Line D shows the voltage

across condenser **C2** which is a linearly increasing charge and a very short discharge time. The charging and discharging occurs at the carrier frequency. The output at **P2** may be used as desired for signalling purposes. The percentage modulation may be varied by varying the amplitude of the modulating signal applied to the grid of tube **V1**.

When amplitude modulated output of sine wave form is desired, the output at point **P2** is passed through a band pass filter which passes the carrier frequency and side bands but attenuates all modulating signal frequencies and all harmonics of the carrier frequency. The output will then be a sine wave, the amplitude of which varies at signal frequency, and will have a wave form as shown in line **E** of Fig. 3. Then an arrangement as shown in Fig. 2 may be used. This embodiment is similar to that of Fig. 1 except as follows. An amplifier tube **V7** has its control grid **36** coupled to the point **P2**. The tube **V7** has its cathode grounded through a cathode resistor **R10** and its grid **36** is coupled to ground by a grid return resistor **R9**. The anode direct current circuit includes a load resistor **R11** and this load resistor supplies output to a band pass filter **60**. The triangular waves appearing at the point **P2** are amplified in the tube **V7** and fed to the band pass filter **60**. The band pass filter **60** will pass the carrier frequency and the side bands but will attenuate all modulating signal frequencies and all harmonics of the carrier frequency. The output will be varying amplitude sine waves of a carrier frequency corresponding to the frequency of the pulse energy impressed at the input **20**. The form of the output is shown in line **E** of Fig. 3.

When the circuit is to be used as a de-modulator or re-modulator, it is modified as illustrated in Fig. 4. The arrangement of Fig. 4 is similar to the arrangement of Fig. 1 except in the following respects. In Fig. 4, the signal applied at the leads **20** is frequency modulated square waves. This frequency modulated square wave energy is fed, as in Fig. 1, over a differentiating network **C1**, **R3** which forms pulses as shown in line **A** of Fig. 5. These pulses are passed to a one-way valve tube to the cathode of the trigger circuit tube **V5**. No signal is fed to the control grid of tube **V1**. On the contrary, this tube **V1** is of fixed gain adjusted as desired to supply the desired charging current to point **P2** and condenser **C1**. By keeping the potential between the grid and cathode of tube **V1**, constant, the charging current is maintained constant irrespective of variations in the potential on the anode of tube **V1**. The pulses derived from the frequency modulated signal as are illustrated in line **A** of Fig. 5, are of a frequency which varies in accordance with the modulation magnitude. Here the signal is assumed to consist of 3 frequencies, **F**, **2F** and **3F**. This frequency modulated signal is differentiated by capacitor **C1** and resistor **R3** and the negative pulse is passed by one-way valve tube **V2** to the cathode of trigger tube **V5** at point **P1**. The potential at point **P1** is as illustrated in line **B** of Fig. 5. The voltage developed across **C2** and **P1** is proportional to **T** and inversely proportional to **F**. Each negative pulse will fire the trigger circuit as desired above. Due to the varying frequency of the carrier impressed at **20**, the time interval between these negative pulses appearing at point **P1** varies. Since the charging current from tube **V1** to capacitor **C2** is of fixed value, the voltage across capacitor **C2** is propor-

tional to time. The frequency modulated signal thus fires the trigger circuit at varying intervals depending on its frequency. Where the frequencies are high, the intervals between firings are of short duration. The tube **V1** then has less chance to charge up capacitor **C2** and the same is not charged very much. When the modulation frequency of the carrier at **20** is low the intervals between firings of the trigger circuits are longer and capacitor **C2** is charged to a higher negative voltage. The output at the point **P2** is of triangular wave form and of varying amplitude and varying frequency. This output then has a wave form as illustrated in line **C** of Fig. 5. Line **3** shows the voltage across **C2**. At frequency **F**, the voltage across **C2** reaches a value **2E**, where

$$\frac{I}{C} = k = 2, \text{ and } \frac{1}{F} = T, \frac{1}{2F} = \frac{T}{2}, \text{ and } \frac{1}{3F} = \frac{T}{3}$$

At frequency **2F** the voltage across **C2** reaches

$$\frac{2E}{2}$$

and at frequency **3F** the voltage across **C2** reaches

$$\frac{2E}{3}$$

The value **k=2** is strictly arbitrary and was chosen to make the relationship of the output D.-C. voltages for the different frequencies readily discernible. The amplitude of this wave is inversely proportional to the frequency of the frequency modulated carrier at the input **20**. The amplitude is proportional to time **T** which is

$$\frac{1}{F}$$

The frequency of this triangular wave is the same as the frequency of the carrier supplied at **20**.

Now, if a low pass filter is connected to the load resistor of tube **V7** and arranged to pass only the signal modulating the frequency of the carrier impressed at **20**, the output of the filter will be the original signal used to modulate the carrier. The signal is then represented by line **D** of Fig. 5. The highest modulation frequency must, of course, be lower in frequency than the lowest carrier frequency.

Where it is desired to convert the frequency modulated carrier at input leads **20** to a carrier which is correspondingly amplitude and frequency modulated, a band pass filter may be connected to the plate of tube **V1**. This filter is then arranged to pass the entire frequency modulated wave band comprising the carrier and both of its side bands. The entire spectrum is passed by the band pass filter **60**. The filter **60** attenuates or excludes the modulation frequencies and harmonics of the carrier. The output will then consist of varying frequency, sine waves of varying amplitude as illustrated in line **E** of Fig. 5. The amplitude of these waves is proportional to **T**, which is

$$\frac{1}{F}$$

What is claimed is:

1. In a signalling apparatus, a trigger circuit comprising two tubes having electrodes and connections such that the circuit has one condition of stability to which it returns at a predetermined time interval after it is tripped therefrom, a capacitor, a discharging path for the capacitor including the impedance between the electrodes of one of said tubes, a charging path for said ca-

pacitor including a source of continuous unidirectional current, connections to said trigger circuit for tripping the same from said one condition of stability at a recurring rate and an output circuit coupled to said capacitor.

2. In a signalling apparatus, a trigger circuit comprising two tubes having electrodes and connections such that the circuit has one condition of stability to which it returns at a predetermined time interval after it is tripped therefrom, a capacitor, a discharging path for the capacitor including the impedance between the electrodes of one of said tubes, a charging path for said capacitor including a source of continuous unidirectional current the magnitude of which varies with signals, a source of alternating voltage of constant frequency connected to said trigger circuit for tripping the same from said one condition of stability at a constant rate and an output circuit coupled to said capacitor.

3. Apparatus as recited in claim 2 wherein said output circuit is coupled to said capacitor by a filter circuit.

4. Apparatus as recited in claim 3 wherein said filter is of the band pass type with the band pass substantially centered on the frequency of said alternating voltage of constant frequency.

5. In a signalling apparatus, a trigger circuit comprising two tubes having electrodes and connections such that the circuit has one condition of stability to which it returns at a predetermined time interval after it is tripped therefrom, a capacitor, a discharging path for the capacitor including the impedance between the electrodes of one of said tubes, a charging path for said capacitor including a source of continuous unidirectional current of constant magnitude, a source of alternating voltage of a frequency which varies in accordance with signals coupled to said trigger circuit for tripping the same from said one condition of stability at a varying rate and an output circuit coupled to said capacitor.

6. Apparatus as recited in claim 5 wherein said output circuit is coupled to said capacitor by a filter circuit.

7. Apparatus as recited in claim 6 wherein said filter is of the low pass type with its cut-off above the highest signal frequency.

8. Apparatus as recited in claim 6 wherein said filter is of the band pass type with its band pass substantially centered on the frequency of said alternating voltage.

9. In a signalling apparatus, a trigger circuit comprising two tubes having electrodes and connections such that it has one condition of stability to which it returns at a predetermined time interval after it is tripped therefrom, a condenser, a discharging path therefor including the impedance between electrodes of one of said tubes, a third tube having an anode, a cathode and a grid operated so that the anode current flow in the tube is linearly related to its grid potential irrespective of anode potential variations, a charging path for said condenser including the impedance between the anode and cathode of the third tube, connections to said trigger circuit for tripping the same at a rate such that the time intervals between tripping operation are greater than said first time intervals and an output circuit coupled to said condenser.

10. In a signalling apparatus, a trigger circuit comprising two tubes having electrodes and con-

nnections such that it has one condition of stability to which it returns at a predetermined time interval after it is tripped therefrom, a condenser, a discharging path therefor including the impedance between electrodes of one of said tubes, a third tube having an anode, a cathode and a grid operated so that the anode current flow in the tube is linearly related to its grid potential irrespective of anode potential variations, a charging path for said condenser including the impedance between the anode and cathode of the third tube, connections to the electrode of said third tube to modulate the potential therein in accordance with signals, connections to said trigger circuit for tripping the same at a rate such that the time intervals between tripping operation is greater than said first time intervals and an output circuit coupled to said condenser.

11. Apparatus as recited in claim 10 wherein a filter circuit is in the coupling to said output circuit.

12. In a signalling apparatus, a trigger circuit comprising two tubes having electrodes and connections such that it has one condition of stability to which it returns at a predetermined time interval after it is tripped therefrom, a condenser, a discharging path therefor including the impedance between electrodes of one of said tubes, a third tube having an anode, a cathode and a grid operated so that the anode current flow in the tube is linearly related to its grid potential irrespective of anode potential variations, a charging path for said condenser including the impedance between the anode and cathode of the third tube, a source of voltage the frequency of which varies in accordance with signals from said source, connections to said trigger circuit for tripping the same at a rate such that the time intervals between tripping operation is greater than said first time intervals and an output circuit connected to said condenser.

13. Apparatus as recited in claim 12 including a filter circuit in said last named coupling.

14. In a signalling apparatus, a trigger comprising two tubes having electrodes and connections such that it has one condition of stability to which it returns at a predetermined time interval after it is tripped therefrom, a condenser and a discharging path therefor including one of said tubes, a third tube having an anode, a cathode and a grid operated so that the current flow in the tube is linearly related to its grid potential irrespective of anode potential variations, a charging path for said condenser including the impedance between the anode and cathode of the third tube, a network for modifying the shape of recurring potentials of carrier frequency connected to said trigger circuit for firing the same at said recurring rate and an output circuit connected to said condenser.
